UNITED STATES PATENT OFFICE.

GEORGE W. PAULUS, OF GRAND RAPIDS, WISCONSIN.

PENCIL-HOLDER.

1,226,992.

Specification of Letters Patent.

Patented May 22, 1917.

Application filed April 4, 1916. Serial No. 88,941.

To all whom it may concern:

Be it known that I, GEORGE W. PAULUS, a citizen of the United States, and a resident of Grand Rapids, in the county of 5 Wood and State of Wisconsin, have invented certain new and useful Improvements in Pencil-Holders, of which the following is a specification.

My invention relates to holders for pencils, although adapted for use with pen-holders, brushes, erasers, or other articles, and the main object is to provide such holders and means for securing the same in convenient positions for instant use, as upon 10 the backs of tablets, upon school blank books, upon memorandum books, note book covers, etc., and in some forms may be used on the flat portions of covers, on desks, on a wall, or in any other convenient and suitable place.

The holder itself is formed of tin, iron, brass, steel, or other stiff material and serves to protect the point of a pencil or pen, as well as for the purpose above stated.

Various methods of securing the holder in place may be employed, several of such being illustrated, and the holder may also be made to serve as a lock for the covers of a book.

My invention is fully described in the following specification, of which the accompanying drawings form a part, in which like characters refer to like parts in each of the views, and in which:—

Figure 1 is a side view of a note book, tablet, or pad, provided with one form of my holder, partly broken away;

Fig. 2 is an enlarged section taken on the line 2—2 of Fig. 1;

Fig. 3 is a view similar to Fig. 2, showing a modification;

Fig. 4 is a fragmentary view of a modified form of holder held upon the flat surface of a book, tablet, or pad;

Fig. 5 is an enlarged section taken on the line 5—5 of Fig. 4.

Fig. 6 is a fragmentary side view of a book the covers of which are held together by another form of holder;

Fig. 7 is an enlarged section taken on the line 7—7 of Fig. 6.

Fig. 8 is a view similar to Fig. 6, but showing another form of locking holder; and

Fig. 9 is an enlarged section taken on the line 9—9 of Fig. 8.

In the different forms illustrated and about to be described, there are two features common to all, the open sided cylindrical member 15 and the bead 16 which serves the 60 dual purpose of a means for securing the member 15 in place and of stiffening the device as a whole.

In the form shown in Figs. 1 and 2, the sheet metal or other stiff material forming the member 15 and bead 16 is continued to form a flat member 17 having slots 18 therein. In securing this form to the back or cover, whichever it may be, 19, of a pad, tablet, or book, a strip 20 of paper or fabric 65 is employed, a part thereof being pasted to the surface of the back 19, preferably as shown at 21 to the rear surface of the said back, the strip 20 being then looped within the bead 16, as shown at 22, and locked 70 therein by means of a member 23 of wood, wire, twine, etc., after which the strip 20 is cut to form two tongues 24 which are passed outwardly through the slots 18, the member 25 and tongues 24 being then pasted 75 to the back or cover 19, thus holding the pencil holder in place at the edge of the back or cover. With respect to the bead 16 it will be noted that in all forms in which a hard filler member 23 is used the open side 80 of the bead is of materially less width than the diameter of the bead, thereby preventing lateral withdrawal of the strip 20 and filler 23, and I may compress the bead at desired points to prevent withdrawal of the 85 said strip and filler longitudinally of the bead, this not requiring illustration as it is merely an expedient.

In the form shown in Fig. 3 the member 17 is not used nor provided, the edge of the 95 back or cover 19 being passed within the bead 16 and locked by the filler 23 against lateral removal.

The form shown in Figs. 4 and 5 is adapted for use on flat surfaces, whereas the preceding forms were all at the edges of the back or cover 19, this form providing a supplemental cylindrical member 15^a whereby two pencils may be held instead of but one, and this form is held in place by means of 100 a strip 34 looped within the bead 16, and held therein by means of the filler 23, and then pasted to the back or cover 19.

The holder shown in Figs. 6 and 7 is identical with the one shown in Figs. 1 and 2, 110 but I form a lock therewith for the covers 19 and 19^a by pasting a strip 35 on the cover

19^a and extending well beyond the edge of said cover to form a tongue 36, the portions cut from the ends of said tongue being bent inwardly of the cover 19^a to form holding flaps 37. In this form, upon closing a book, the tongue 36 is passed within the cylindrical member 15 and, when the pencil 38 is forced longitudinally through said member 15 with its point foremost, the tongue 36 is locked within said member 15 against removal, this strip 35 and tongue 36 being of paper or fabric of sufficient strength and pliability to serve as stated.

In all of the forms so far described, the bead 16 was formed at the open side of the cylindrical member 15 and served, with the edge of the sheet forming said member 15, to form the opening into said cylindrical member, but in the form shown in Figs. 8 and 9 I form the bead on the opposite side of the metal forming the cylindrical member 15, as shown at 39, Fig. 9, and I lock the edge of the cover 19 within the bead by means of a filler in the manner described with reference to Fig. 3. In this form, the cover 19^a has a paper or fabric strip 40 pasted to both sides thereof and projecting beyond the edge thereof to form a loop 41 adjacent one end of the cylindrical member 15, the pencil 38 passing through both the member 15 and the loop 41 locking the covers 19 and 19^a together.

While my invention is designed primarily for use with pads, tablets, and books, I obviously do not limit myself to such uses, the form shown in Figs. 4 and 5 being particularly adaptable to any flat surface, such as a desk, a wall, or any equivalent, but I do

intend to employ the cylindrical member 15, bead 18, and filler 23, in all forms, regardless of the exact shape of either, or of the material of which they are composed.

Having fully described my invention, what I claim as new, and desire to secure by Letters Patent, is:—

1. A device of the class described, comprising a split cylindrical member, adapted to receive a pencil, having a split bead at one of its lateral edges, and means within said bead for securing said device to a back or cover.

2. A device of the class described, comprising a split cylindrical member, adapted to receive a pencil, having a split bead at one of its lateral edges, and a filler within said bead for securing said device to a back or cover.

3. A device of the class described, comprising a split cylindrical member, adapted to receive a pencil, having a split bead at one of its lateral edges, a flexible strip looped within said bead and pasted to a book or cover, and a filler within said bead preventing the removal of said strip.

4. A device of the class described, comprising a split cylindrical member, adapted to receive a pencil, having a split bead at one of its lateral edges, means within said bead for securing said device to one cover of a book, and means secured to the other cover of said book engaged by said pencil to lock said covers in closed position.

GEORGE W. PAULUS.
